SPECIFICATION forming part of Design No. 14,020, dated July 3, 1883.

Application filed March 16, 1883. Term of patent 3½ years.

To all whom it may concern:

Be it known that I, ARTHUR L. HALLIDAY, of New York, in the county and State of New York, have invented a new and original Design 5 for Carpets, of which the following is a specification.

The accompanying photograph illustrates a face view of my new design for carpets.

This invention relates to a new design for 10 carpets and analogous fabrics; and it consists of the new configuration of groups and figures that make up the groundwork of the carpet.

The carpet is composed of a number of 15 squares set side by side, resembling the squares of a checker-board, all the squares containing ornamentation, the numerous squares *o* each containing an ornamentation of circular figures, being so arranged as to come alternately with and between the other ornamented 20 squares. Of the other squares, *r* contains an ornamentation resembling a branch with leaves on it. *z* has also a branch-like ornamentation. *w* resembles a flower on a speckled background. *b* has a leafy spray. *a* has a branch with circular flowers. *d* has a flower on a speckled background. *s* is ornamented with two star-like flowers. *n* contains the ornamentation of a leafy branch. *t* has a branch with circular leaves or berries. *v* is ornamented with a curv-

ing leafy figure; *e*, with a branch bearing 30 leaves and two larger circular flowers. *f* contains an ornamentation of a branch and leaves, and *g* ornamentation of a single leaf. *h* is ornamented with a leafy branch, and *x* with a branch bearing circular flowers and leaves. 35
